CLAIM

The ornamental design for a combined barbecue grill and spit, substantially as shown and described.

DESCRIPTION

FIG. 1 is a top, front, and right side perspective view of a combined barbecue grill and spit showing my new design, the hose is shown in broken lines for illustrative purposes only and forms no part of the claimed design; FIG. 2 is a bottom, rear and left side perspective view thereof;

FIG. 3 is a top, front, and left side perspective view thereof in a closed position.

FIG. 1.

FIG. 2.

FIG. 3.
